UNITED STATES PATENT OFFICE.

AUGUST STAMM, OF NEW YORK, N. Y.

HAT-GUARD.

SPECIFICATION forming part of Letters Patent No. 701,639, dated June 3, 1902.

Application filed March 12, 1902. Serial No. 97,920. (No model.)

To all whom it may concern:

Be it known that I, AUGUST STAMM, a citizen of the United States, residing in New York, borough of Manhattan and State of New York, 5 have invented certain new and useful Improvements in Hat-Guards, of which the following is a specification.

This invention relates to an improved hat-guard which is intended for use mainly with 10 straw hats, but which can also be used with any other soft or stiff hat; and the invention consists of a hat-guard which comprises a cord, a tapering pin attached to one end of the cord and adapted to be pierced through 15 the body of the hat, and a clamping device secured at the opposite end of the cord provided with two openings and a V-shaped clamping-hook.

In the accompanying drawings, Figure 1 is 20 a perspective view of a straw hat with my improved hat-guard applied thereto, showing the same in position when not in use. Fig. 2 is a perspective view showing the hat-guard in position ready for use. Fig. 3 is a 25 side elevation of the hat-guard, showing the same applied to a hat and drawn on a larger scale. Fig. 4 is a horizontal section on line 4 4, Fig. 3, and Figs. 5 and 6 are respectively side views of the clamping device for 30 the hat-guard and the tapering pin for securing the hat-guard to the body of the hat.

Similar letters of reference indicate corresponding parts.

Referring to the drawings, A represents a 35 straw hat to the body of which my improved hat-guard is applied. The hat-guard consists of three parts—namely, a cord d, a flat tapering pin e, and a clamping device f. One end of the cord d is attached to the 40 clamping device f, which is provided for this purpose with two openings or eyes f', the cord being passed from the rear of the clamping device f through one of the openings f' to the front, then through the other 45 opening f' to the rear, where the cord is tied into a knot d', so as to prevent its detaching from the clamping device f. The front end of the clamping device f is provided with a V-shaped hook f², that serves for clamping

the cord tightly in position around the body 50 of the hat when not required for use, as shown in Figs. 1, 3, and 4, the cord being for this purpose passed into the tapering recess of the V-shaped hook, which bites sufficiently into the cord to firmly retain the same in the 55 clamping device.

For attaching the cord to the body of the hat the flat tapering pin e is placed on the other end of the cord from the clamping device f, the cord being pulled through the hole 60 e' in the body of the pin and tied into a knot d². The pin is then pierced through the body of the hat near the brim until it has passed through the same, leaving the knot d² to remain outside of the hat A. Then by 65 pulling upon the cord from without the hat the pin assumes a position in contact with the inside of the hat-body, as shown in Fig. 4. The body of the cord is then placed 70 around the body of the hat, the V-shaped hook f² of the clamping device engaging the cord, as shown in Figs. 1 and 3, so that the cord is tightly held in position on the hat. When required for use, the V-shaped clamping device is detached from the cord, which 75 latter is removed from around the body of the hat, as shown in Fig. 2, after which the clamping device is passed through the buttonhole of the lapel of the coat and fastened in any desirable manner. 80

The clamping device is preferably made of sheet metal and stamped into the form of a snake, as shown in Fig. 5, which adds attractiveness to the hat-guard and forms a neat, convenient, and readily-applied device 85 for preventing the hat from being carried away by the wind.

Having thus described my invention, I claim as new and desire to secure by Letters Patent— 90

1. A hat-guard, consisting of a cord, a flat pointed pin attached to one end of said cord, and a clamping device attached to the opposite end of the cord and provided with a V-shaped hook for engaging with the cord, substantially as set forth. 95

2. A hat-guard, consisting of a cord of proper length, a flat pointed pin provided

with an opening and attached to one end of
the cord, and a clamping device provided
with two openings or eyes for attachment
with the opposite end of the cord, said clamp-
5 ing device being provided with a V-shaped
hook at one end, substantially as set forth.
In testimony that I claim the foregoing as

my invention I have signed my name in pres-
ence of two subscribing witnesses.

AUGUST STAMM.
